(57) **CLAIM**

The ornamental design for a base transceiver station for mobile network, as shown.

DESCRIPTION

FIG. 1 is an upper perspective front view of the base transceiver station for mobile network;

FIG. 2 is a front side view thereof;

FIG. 3 is a right view thereof;

FIG. 4 is a left side view thereof;

FIG. 5 is a rear view thereof;

FIG. 6 is a bottom plan view thereof; and,

FIG. 7 is a top plan view thereof.
